US0D1066725S

(12) **United States Design Patent** (10) **Patent No.:** **US D1,066,725 S**
(45) **Date of Patent:** **** Mar. 11, 2025**

(54) **SALIVA TEST DEVICE**

(71) Applicant: **Hangzhou Biotest Biotech Co., LTD.,**
Zhejiang (CN)

(72) Inventors: **Shujiang Wu**, Zhejiang (CN); **Liang Hong**, Zhejiang (CN)

(73) Assignee: **HANGZHOU BIOTEST BIOTECH CO., LTD.**, Hangzhou (CN)

(**) Term: **15 Years**

(21) Appl. No.: **29/859,171**

(22) Filed: **Nov. 8, 2022**

(30) **Foreign Application Priority Data**

Oct. 21, 2022 (CN) 202230697901.6

(51) **LOC (15) Cl.** **24-02**

(57) **CLAIM**

The ornamental design for a saliva test device as shown and described.

DESCRIPTION

FIG. 1 is a perspective view of a saliva test device showing our new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view thereof shown in state of use. The broken lines depict portions of the environment structure that form no part of the claimed design.

1 Claim, 9 Drawing Sheets
